UNITED STATES PATENT OFFICE.

HARRY T. KINGSBURY, OF KEENE, NEW HAMPSHIRE.

TOY AUTOMOBILE.

1,208,572.

Specification of Letters Patent. Patented Dec. 12, 1916.

Application filed May 8, 1913. Serial No. 766,334.

To all whom it may concern:

Be it known that I, HARRY T. KINGSBURY, a citizen of the United States, residing at Keene, in the county of Cheshire, State of New Hampshire, have invented certain new and useful Improvements in Toy Automobiles, of which the following is a description, reference being had to the accompanying drawing and to the figures of reference 10 marked thereon.

My invention relates to improvements in toy automobiles.

The object of my invention is to provide a body of a toy automobile in which the 15 sides and bottom are made of a single piece of metal, and in which the forward ends of the sides are drawn inwardly to form the sides of the hoods.

Another object is to provide a toy of this 20 character in which the top of the hood is readily attached to the sides of the hood and in which a cast metal radiator plate may be readily attached.

A still further object of my invention is 25 to provide a simple, cheap and more effective manner of forming the body and hood of an automobile, having certain details of structure hereinafter more fully described.

In the accompanying drawings,—Figure 30 1 is a perspective view of an automobile constructed according to my invention; Fig. 2 is a bottom plan view, showing the manner of securing the seat to the body portion; Fig. 3 is a transverse sectional view taken 35 through the hood; Fig. 4 is a transverse sectional view taken on the line of the seat; and Fig. 5 is a longitudinal sectional view.

Referring now to the drawing, 1 represents my improved toy automobile, which, 40 as shown, has the bottom 2 and sides 3 of the body formed of a single sheet of metal, bent as shown, and sides drawn inwardly as indicated at 4 to form the sides of the hood. The bottom is cut away as indicated at 5, in 45 order that the sides may be more readily drawn inwardly to form the hood, and to also allow for the bushing flange 5 to rotate without striking bottom 2. The upper edge of the inwardly drawn sides forming 50 the sides of the hood are bent downwardly at 7, and into these fit the upwardly turned edges 8 of the top 9 of the hood, and said flanges are clamped together forming a seam similar to a can seam, whereby the top is 55 locked to the sides of the hood. The rear end of the top of the hood is flared out-

wardly, as indicated at 10, to give the same effect as a real automobile.

Within the body of the automobile, the plate 11 is placed, which is slanting, as 60 shown in Fig. 5, and is provided with a vertical elongated slot 11', through which the steering post 12 passes. The lower end of steering post is split at 13, and extends through an opening 14 in the bottom of 65 the hood. Said split end is turned over, as indicated at 15, whereby the steering post is free to move up and down within the slot 11'. Carried by the upper end of the steering post is the wheel 16, and by this 70 structure it will be seen that the steering wheel is lowered, so that it comes below the upper end of the hood, for saving space for shipment, and also allows the wheel to readily be raised, so that the figure toy 75 driver may be placed in the machine.

The forward ends of the sides of the hood are provided with forwardly extending lugs 17, which extend through slots 18 into the edges of the radiator plate 19. Surrounding 80 the extreme forward edge of the top, sides and the bottom of the hood is a frame 20. This frame has an inwardly projecting web 21 against the outer face of which the plate 19 rests, the lug 17 being bent down against 85 the outer face of the plate. The bottom, sides and top of the hood extend underneath the flange of the frame and rest against the web thereof. This serves as an effective means of holding the radiator plate in place 90 and binding together the bottom, sides and ends of the hood. The radiator plate is provided with a series of vertical slots which gives a realistic effect thereto.

The rear end of the sides of the car are 95 provided with a plate 22, which carries the seat 23, and is held in said position by means of the lugs 24 at the rear, carried by the bottom and the forward lugs 24', carried by the vertical portion 25, passing through openings 26 in the bottom 2.

The bottom 2 adjacent the rear end is provided with a cut away portion 27, which allows space for the large driving gear not shown. The metal of this cut away portion 105 forms the two downwardly extending ears 29 and 30, having elongated slots 31 extending from their lower ends, and in which is mounted the rear drive axle 32. The ears 29 and 30 formed by said slots are turned 110 inwardly to retain the axle in the slots, but the said slot is of sufficient length to allow

of a vertical movement of the axle, whereby the ears may be bent to aline the wheels without frictionally engaging the axle. Pivoted to the forward end of the bottom 5 is a transverse bar 34, having downwardly extending ears 35 and 36, having elongated slots 37, through which the forward axle 38 passes. By means of the slot the alinement of the front wheels may be made.

10 Having thus described my invention, what I claim as new and desire to secure by Letters Patent, is:—

1. A toy automobile comprising a sheet of metal bent to form the bottom and the sides 15 of the body, the sides of the body having outwardly projecting flanges at the forward ends thereof in the region of the hood and the top having inwardly projecting flanges adapted to interlock with the flanges on the 20 sides, a radiator plate for closing the front end of the hood, and a frame surrounding the bottom, sides and top of the hood against which said radiator plate is clamped.

2. A toy automobile comprising a sheet of metal bent to form the bottom and the sides, 25 a top interlocked with the sides of the body at the forward ends thereof for forming the hood, a radiator plate for closing the forward end of the hood, said plate having slots 30 formed therein, lugs carried by the top and side members adapted to extend through said slots and be folded against the front face of the radiator plate, a frame surrounding the bottom, sides and top of the hood, 35 said frame having a web adapted to be engaged by the side members and top of the hood and against which the radiator plate is clamped.

3. A toy automobile comprising a sheet of metal bent to form the bottom and the sides, 40 a top interlocked with the sides of the body at the forward ends thereof for forming the hood, a radiator plate for closing the forward end of the hood, said plate having slots

formed therein, lugs carried by the top and 45 side members adapted to extend through said slots and be folded against the front face of the radiator plate, a frame surrounding the bottom, sides and top of the hood, 50 said frame having a web adapted to be engaged by the side members and top of the hood and against which the radiator plate is clamped, and a plate resting on the sides of the body and carrying a seat, said plate being secured thereon by lugs carried by the 55 plate and bottom.

4. A toy automobile comprising a sheet of metal bent to form the bottom and the sides, 60 a top interlocked with the sides of the body at the forward ends thereof for forming the hood, a radiator plate for closing the forward end of the hood, said plate having slots 65 formed therein, lugs carried by the top and side members adapted to extend through said slots and be folded against the front face of the radiator plate, a frame surrounding the bottom, sides and top of the hood, 70 said frame having a web adapted to be engaged by the side members and top of the hood and against which the radiator plate is clamped, a front plate secured to the rear end of the hood for closing the same, said plate having a vertical slot therethrough for the steering wheel post.

5. A toy automobile comprising a sheet of 75 metal bent to form the bottom and sides of the body, a top resting upon the sides, a radiator plate closing the front of the hood, and a frame surrounding the bottom, sides and top of the hood against which said 80 radiator plate is clamped.

In testimony whereof, I affix my signature, in the presence of two witnesses.

HARRY T. KINGSBURY.
